(57) **CLAIM**

The ornamental design for a magnifier, as shown and described.

DESCRIPTION

FIG. 1 is a front view of the magnifier;

FIG. 2 is a rear view of FIG. 1;

FIG. 3 is a plan view of FIG. 1;

FIG. 4 is a bottom view of FIG. 1,

FIG. 5 is a right side view of FIG. 1, the left side view being a mirror image;

FIG. 6 is a cross sectional view of FIG. 1;

FIG. 7 is a cross sectional view of FIG. 1; and

FIG. 8 is a front elevational view thereof; and,

FIG. 9 is a front elevational view with the magnifier lens pivoted outside of its case.

The broken line showing of the rope in FIG. 8 and the pivoted lens in FIG. 9 is for illustrative purposes and forms no part of the claimed design.
